US00D410916S

United States Patent [19] Oba

[11] Patent Number: Des. 410,916
[45] Date of Patent: ** Jun. 15, 1999

[54] CASE FOR SEMICONDUCTOR ELEMENT

[75] Inventor: **Haruo Oba**, Tokyo, Japan

[73] Assignee: **Sony Corporation**, Tokyo, Japan

[**] Term: 14 Years

[21] Appl. No.: 29/073,021

[22] Filed: Jun. 27, 1997

[51] LOC (6) Cl. 14-99

[52] U.S. Cl. D14/120

[57] CLAIM

The ornamental design for a case for a semiconductor element, as shown and described.

DESCRIPTION

FIG. 1 is a perspective view of a case for a semiconductor element showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and,

FIG. 7 is a rear elevational view thereof.
